CHARLES STAFFORD, OF ELIZABETH, NEW JERSEY, ASSIGNOR TO THE SINGER
MANUFACTURING COMPANY, A CORPORATION OF NEW JERSEY.

ADJUSTABLE HEMMER.

1,153,459.

Specification of Letters Patent. Patented Sept. 14, 1915.

Application filed June 26, 1913. Serial No. 775,846.

To all whom it may concern:

Be it known that I, CHARLES STAFFORD, citizen of the United States, residing at Elizabeth, in the county of Union and State 5 of New Jersey, have invented certain new and useful Improvements in Adjustable Hemmers, of which the following is a specification, reference being had therein to the accompanying drawings.

10 This invention relates to an improvement in adjustable hemmers for sewing machines and more especially to means whereby the parts are permanently connected and so arranged that the attachment may be adjusted 15 to form hems of any width.

According to the present invention, the hemmer is constructed of four pieces of sheet metal suitably shaped by dies or the like, the same being riveted together and 20 thus fixed against movement with the exception of the guide member which is permanently connected to the remaining members by means of a headed set-screw which passes through a slot formed in said guide member 25 to permit longitudinal adjustment of the latter relatively to the edge-turning or curling members. The guide member serves to turn or fold the material, along a line distanced from its edge according to the width 30 of hem desired, so that its under face will be superposed upon its upper face, and its edge guided to the curling members which curl or inturn said edge under the superposed 35 ply.

40 In hemmers of the present type the guide member in each case has a limited adjustment only, usually for a hem of one-inch maximum width; and when it is desired to form a hem of considerable width, as for example, a pillow case hem or the like, the folding operation is performed by other means, the guide member discarded, and the edge curling members alone are used. In such case it has been necessary to disengage 45 the parts and to wholly remove the guide member, scale-pointer and set-screw, so that such parts will not obstruct the free movement of the material during the edge curling operation of the attachment. Several 50 disadvantages are present in such arrangement—first, the unskilled operator may improperly reassemble the parts; secondly, some of the parts are so small that loss is frequent; thirdly, the removal and replacement of the set-screw serves to break down 55

the threads in the thin sheet metal support for the guide member, rendering the latter useless; and fourthly, the difficulty and annoyance of removing and reassembling the small parts is considerable.

60 In the present invention, when it is desired to complete a hem of greater width than that permitted by the guide member in active position, the latter may be moved longitudinally to one extreme position and 65 then swung upon its set-screw as an axis and out of the path of the material. When it is desired to use the guide member the movement is reversed, thereby placing it again into active position.

70 In the drawings, Figure 1 is a top view of the hemmer with its parts assembled, showing in dotted lines, the guide member in inactive position. Fig. 2 is a perspective view of the same, the guide member being 75 in active position. Fig. 3 is a bottom view of the same and Figs. 4 and 5 are detail views of the guide member and the bracket scale-pointer, respectively.

75 Referring to the drawings, 1 represents 80 the foot of the hemmer, the same being provided with shank 2 adapted to be secured to the presser-bar of a sewing machine. The foot-piece is formed with two arms or prongs 3 and 4, and is provided with an intermediate needle-aperture 5, as customary in attachments of the present type. Secured to the under faces of prongs 3 and 4 is a smoothing plate 6 which is formed with an intermediate portion 7 bent over the inner 85 edge of prong 3 and secured to the upper face thereof by rivet *a*, which extends through said prong and the lower portion of the smoothing plate. Intermediate portion 7 of the smoothing plate is rounded to 90 provide a smoothing surface under which the fabric may slide without creating friction. The outer end of said smoothing plate is bent upwardly and bent inwardly to form the spring curling finger 8, its extreme end 95 being bent downwardly and upon itself to form curling hook 9. The portion 7^x of said smoothing plate, forming the base for curling finger 8, is secured to prong 3 by means of rivet *b*.

100 The outer end of prong 4 is inturned toward the hooked end of curling finger 8, and is properly shaped to form an arbor or curling point 10, said curling point being 105 disposed slightly in advance of said curling 110

hook and also slightly above its lower fabric-engaging face, to coact with said hook in its curling action upon the edge of the fabric, in the usual manner.

5 Secured to the outer face of prong 4 is foot 11' of bracket 11, the remaining foot 11" of said bracket being formed with an aperture for the reception of set-screw 13, which passes through slot 15*, formed in 10 guide member 15 and thence passes through prong 4, being headed below the lower face of the latter, in order to permit a limited movement only of said set-screw. The inner portion of guide 15 is formed with an 15 upwardly extending spring-arm 16 which, at its end, is provided with a downwardly extending curved guide-lip 17, disposed adjacent guide-tongue 18 formed at the outer end of the slotted portion of the guide member, being a continuation of the depending outer edge 20 of the same. Bracket 11 provides a U-shaped channel adapted to receive spring-arm 16 and to aid set-screw 13 in 20 maintaining the guide member in its various adjusted positions. Said bracket is provided with a pointer 14 which coöperates with a graduating scale formed upon the upper face of spring-arm 16 to indicate the various positions of adjustment of the guide member. It will be seen without further explanation that rotation of set-screw 13 in 25 the proper direction will permit the guide member 15 to be moved longitudinally to vary the width of hem.

30 The attachment having been adjusted to form a hem of the desired width, the material is inserted between guide-lip 17 and guide-finger 18 and is passed over the slotted portion of the guide and under spring-arm 16, the extreme edge of the material to be hemmed passing over curling point 10 and into abutment with the hooked end 9 of curling finger 8. When the presser-foot is lowered depending guide-lip 17 will act as 35 a stop shoulder for the outer edge of the material and will serve to hold the same in proper alinement. In the present instance the attachment is designed to completely fold material into hem formation of varying widths up to a maximum width of one-inch. When, however, it is desired to form a hem of greater width it becomes necessary 40 first to partially fold the material and secondly to remove guide member 15 out of the path of the material. To such end, slot 15* extends sufficiently to the rear of upwardly extending arm 16 to permit the latter to be

drawn beyond foot 11" of bracket-pointer 11. As the inner end of guide member 15 is formed substantially as a quadrant, and as 60 the outer portion of prong 4 adjacent the set-screw is rounded, the guide member may now be swung to the left upon said set-screw 13 and thus be moved to inactive position out of the path of the material. The material may now be folded for any width of hem, and its edge is then placed in position to be engaged by curling hook 9 and curling point 10 in the usual manner.

Having thus set forth the nature of the 70 invention, what I claim herein is:—

1. In a hemming attachment for sewing machines, a foot, edge curling members carried by said foot and including a curling hook and an arbor embraced thereby, a 75 longitudinally adjustable guide-member provided with an arm, and retaining means secured to said foot and engaging said arm to confine the guide-member against lateral movement, the said retaining means being 80 ineffective at a given point of adjustment of the guide-member.

2. In a hemming attachment for sewing machines, a foot, edge-curling members carried by said foot and including a curling 85 hook and an arbor embraced thereby, a longitudinally adjustable guide-member provided with a spring-arm, a bracket adapted to confine said arm against lateral movement and provided with a clamping 90 foot, a set screw adapted to press said clamping foot upon the guide-member, and means whereby said guide-member may be swung laterally upon said set screw as an axis at a given point of adjustment. 95

3. In a hemming attachment for sewing machines, a foot, and an arbor carried thereby, a smoothing plate embracing said foot and formed with a curling finger turned at its free end to provide a curling 100 hook to coact with said arbor, an adjustable guide-member connected to said foot, and means for confining said guide-member against lateral movement, said means being ineffective at a given point of adjustment 105 of said guide-member.

In testimony whereof, I have signed my name to this specification, in the presence of two subscribing witnesses.

CHARLES STAFFORD.
